HENRY METCALF, OF WASHINGTON, DISTRICT OF COLUMBIA.

Letters Patent No. 92,078, dated June 29, 1869.

IMPROVEMENT IN SPEED-INDICATOR FOR VESSELS.

The Schedule referred to in these Letters Patent and making part of the same.

To all whom it may concern:

Be it known that I, HENRY METCALF, of Washington, in the county of Washington, and in the District of Columbia, have invented certain new and useful Improvements in Naval and Current Velocimeter; and do hereby declare that the following is a full, clear, and exact description thereof, reference being had to the accompanying drawings, and to the letters of reference marked thereon, making a part of this specification.

The nature of my invention consists in the construction of a simple device, by means of which the speed of vessels can at once, and accurately, be ascertained.

The accompanying drawing represents a side elevation of my invention.

My velocimeter consists of three parts, a motor, an indicator, and a compensator, with the necessary connections between the parts.

The motor or force-pipe consists of a tube, A, which passes through the bottom of the vessel amidships, tangent to the vertical plane of right section through the centre of gravity, and tangent to the keel, has one or more rectangular turns to the front, presenting thus one or more circular mouths, whose planes are at right angles to the vessel's axis.

The compensatory tube B is in all respects, in length above the water-line, and diameter of bore, &c., exactly the same as the force-pipe, only differing in its lower extremity, which is cut flush with the vessel's bottom, or with the plane of its mouth or mouths, inclined slightly upward and to the rear.

These two pipes are placed in contact, the compensator directly behind the force-pipe, and lead up to any convenient place of observation.

At their upper ends, they each have a very flexible rubber tube, C, about a foot in length, attached to them, which only serves to maintain the connection between them and the indicator D, which consists of a glass tube bent double.

On the branch connected to the force-pipe there is a bulb formed, which is to be half filled with mercury.

This indicator is suspended from a small hook, placed between the upper ends of the pipes, by a wire, or from a point below on gimbals, which allow it to oscillate freely in any direction, like a pendulum.

Between the branches of the indicator there is placed an adjustable scale, E, so that its zero shall be on a level with the mercury's surface in both branches.

The manner of using and operating the parts is as follows:

Suppose only the force-pipe and the gauge to be used. Start the vessel forward, and from the shape of the mouth of the pipe, a column of water is driven up and maintained in it, bringing, from the compression of the air within, a pressure per square inch on the mercury in the bulb equal to that which it sustains from the inertia and friction of the particles of water below,

which pressure, for a given speed, being constant, would maintain the mercury at an equally constant altitude.

This simple plan would do very well, were the line of flotation invariable or never changed permanently from loss or addition of cargo, or temporarily from the rolling and pitching at sea.

It is to obviate the fluctuation due to this change of draught that I introduce my second compensatory tube, which brings upon the mercury, in the branch connected with it, just as great a pressure from any such cause as the force-pipe.

Thus the pressure due to the velocity is the only one capable of changing the level of the mercury, which, from the difference of volume of the bulb and indicating-tube in the former, amounts to relatively nothing.

From the mode of suspending the gauge, no use in the latter tube can supervene from the rocking of the ship alone.

I propose mercury as the fluid to be used, as this will give a scale of convenient length, a column of sixteen inches prox. being supported for a speed of that number of knots an hour.

If, however, a more delicate fluid should be required, giving a greater range for the same difference of speed, the mercury could be lightened, as to its specific gravity, by amalgamation with tin, zinc, or the alkaline metalloids.

Were a larger scale than one thus obtained required, a saturated solution of some salt might be used to diminish the height to which water would go (18' at sixteen knots) if it were left at its natural density.

From the position of the pipe's mouth, being so sheltered by the keel, it would not be injured if the vessel should touch bottom, and being so far under water, would not be liable to being clogged by floating sea-weeds. But even in this case, the action of the gauge depending on a pressure, and not a flow, unless the pipe were hermetically sealed, so as to prevent an indication of variation in velocity, the obstacle to an ascent of the column of water would equally oppose an outward flow, and its attendant diminished pressure. The case being similar to the apparent paradox of two largely unequal volumes of liquid sustaining each other at the same level when communication between them is made.

The scale being graduated according to nautical miles, (a matter easily done, since the pressure and height would vary as the square of the velocity,) a simple inspection would be all that would be necessary to determine the rate.

Should the aperture be closed by barnacles, of the probability of which I cannot judge, they could be removed by unscrewing a section of pipe above the water-line, and then by introducing and pushing down a jointed tool, half-inch gas-pipe being used. I do not think that the most complete instrument would cost, in material, over \$15.

It might be put on ships afloat thus: Bore, at the required places, through the vessel's bottom to the copper, a small hole, say of one inch diameter. Around this, and reaching above the water-line, have a two or three-inch pipe, with a flanged mouth and rubber washer, making, when screwed down to the vessel's bottom timbers, a water-tight joint at its base. Then, with a long auger, cut through the copper. Drop through the hole a line, which grapple for outside, and to the end of which fasten an iron rod, 1, connected with a tight caisson, 2, (with a slide-valve opened by a line passing over the side,) cut to partially fit the bottom, and, for exclusion, provided with a hollow annular rubber washer, 3. Draw the rod through the hole by means of the screw cut on its end. Draw the caisson snugly against the bottom. Pump out the water—the external pressure will keep it in position. Remove the rod at the shoulder 4. Take away the flanged pipe. Put in place the force and compensating-pipes, which, to prevent galvanic action, should have copper ends and lining. Tamp the hole made

securely. Open the valve in the caisson. It is drawn up, leaving the work complete.

Having thus described my invention,

What I claim, and desire to secure by Letters Patent, is—

1. The combination and arrangement of the compensatory tube B, extending down through the vessel, and having its mouth flush with the bottom, with the force-pipe A, parallel with the tube B, and with its mouth at right angles with the axis of the vessel, substantially as set forth.

2. The combination and arrangement of the indicating-scale D E with the tube B and pipe A, and connected by the flexible tubes C O, all substantially as specified.

In testimony that I claim the foregoing, I have hereunto set my hand, this 11th day of May, 1869.

HENRY METCALF.
